(57) **CLAIM**

The ornamental design for a fill light kit, as shown and described.

DESCRIPTION

FIG. 1 is a perspective view showing a first part of a fill light kit;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing a second part of a fill light kit;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of a fill light kit.

The dash-dash broken lines in the drawings depict portions of the fill light kit that form no part of the claimed design.

1 Claim, 17 Drawing Sheets
